SAFETY APPLIANCE FOR MOLDING MACHINES

Henry O. Magnuson, Chicago, Ill., assignor to
 Champion Foundry and Machine Company,
 Chicago, Ill., a corporation of Illinois

Application December 23, 1937, Serial No. 181,257

8 Claims. (Cl. 22—26)

This invention relates to molding machines of the squeeze type, and has reference more particularly to a safety appliance designed to render the manipulation of such machines safe and forestall any possible injury to the operative through carelessness or accident.

Molding machines of this type commonly employ a flask-supporting platform, a platen head that is pivoted either vertically or horizontally so as to swing sidewise or rearwardly between a working position directly overlying the platform and an idle position to one side of the platen, and a pneumatic motor beneath the platform for raising the latter so as to compress and pack the sand in the flask around the pattern, the compression being effected by the relative movement of the platform and head toward each other. A valve, usually opened by the right hand of the operative, is located in the fluid supply line to the motor. It has not infrequently happened that a careless operative, when opening the valve has allowed his other hand to get caught and crushed between the top board of the flask and the head.

Many of these machines also employ a device known as a jolter, operated by a rapidly reciprocating pneumatic motor, for imparting to the flask, during the loading thereof and before the final squeezing operation, a rapid vertical shaking movement to evenly distribute the sand that has been shoveled into the flask; and following this shaking movement the operative adds a final shovelfull of sand and with his hands distributes and lightly packs it to complete the filling of the flask. The valve controlling the admission of compressed air to the jolter motor is usually opened by a handle that is pressed by the knee of the operative. When loading the flask and prior to operating the jolter the head is pushed to one side out of the path of movement of the platform and flask; but sometimes the operative fails to do this, and, while distributing and packing the final shovelfull of sand, he sometimes accidentally hits with his knee and opens the jolter valve, with the result that his hands or wrists get caught and squeezed between the top edge of the open flask and the platen head.

The primary object of this invention has been to provide a useful automatic accessory to a machine of this type that will render impossible either or both of the above described accidents. As will be seen from the following description, the first described accident is prevented by a means which requires both hands of the operative to be engaged in safe positions at the inception of and

during the squeezing operation; and the last described accident is prevented by a means that requires the head to be shifted entirely out of the path of the platform and flask before the motor of the jolter can be operated and to remain in such position until the flask is ready for the squeezing operation.

An illustrative embodiment of this invention is shown in the accompanying drawings, in which—

Fig. 1 is a perspective side view of a portable squeeze-type molding machine embodying my improvement.

Figs. 2, 3 and 4 are diagrammatic plan views, Fig. 2 illustrating the relative positions of the platform and platen head during the flask jolting operation; Fig. 4 illustrating the relative positions of said parts during the flask squeezing operation; and Fig. 3 illustrating intermediate positions of the platen head in and between which both the main operating valves of the squeeze motor and the jolt motor are rendered inoperative.

Fig. 5 is a sectional view of the auxiliary valve in the pipe line leading to the squeeze motor.

Fig. 6 is a similar view of the auxiliary valve in the pipe line leading to the jolt motor.

First briefly describing the parts of the machine that are old and well known, 10 designates the heavy standard carrying the swinging platen head and its arm, and 11 designates a casting secured to the lower front portion of the standard 10 as by bolts 12 and containing the squeeze motor, the cylinder and annular plunger of which are fragmentarily shown at 13 and 14 respectively, and the plunger 15 of the jolt motor which operates in a central bore of the plunger 14. The plunger 14 of the squeeze motor carries on its upper end a platform 16 that supports the flask.

In the upper front portion of the standard 15 is a vertical shaft 17, on which is journaled the elongated hub 18 of a forwardly projecting arm 19 carrying at its free end a vertically adjustable platen head 20.

21 designates the pipe line leading from a source of compressed air or other motive fluid, 45 and communicating with the line 21 is a branch 22 that supplies motive fluid to the squeeze motor and also a branch 23 that supplies motive fluid to the jolt motor. In the line 22 is a main self-closing control valve indicated at 24 that is 50 opened by the operative by depressing a pivoted handle 25 conveniently accessible from the front of the machine; and in the line 23 is a main self-closing control valve indicated at 26 that is so located as to be conveniently opened by the op- 55

erator by pressing his knee against a depending valve handle 27.

I have herein shown a portable machine where-
in the standard 10 and the casting 11 are sup-
ported on a rear wheel 28 and a pair of front
wheels 29; but this portable feature has no rela-
tion to my present improvement, the latter being
equally applicable to stationary machines.

Coming now to those features wherein my pres-
ent improvement resides, in the branch line
22 that serves the squeeze motor is inserted an
auxiliary valve designated as an entirety by 30
and shown in enlarged section in Fig. 5. This
valve is in itself an old and well known type of
valve and comprises a casting formed with op-
posed tapped branches 31 and 32 for insertion
into the pipe line served thereby, a central cham-
ber divided by a bridge 33 formed with a valve
seat 34, and a plunger valve 35 slideable in a cylin-
drical guide 36 constituting a branch of the cast-
ing 30. The valve 35 has a gasket 37 cooperating
with the seat 34, and in rear of the valve is a
spring 38 footed on a nut 39 and forcing the
valve 35 to its seat. To balance the air pressure
25 on opposite sides of the valve when the latter is
open, and to enable the air to assist the spring in
holding the valve closed, the valve body is formed
with a pair of opposed bleed ducts 40. On the
face of the valve body 35 is formed a central
30 socket 41 that receives the inner end of a stem 42
that is slidably mounted in and projects beyond a
packed bearing 43.

On the upper end of the hub 18 of the arm 19
is a laterally projecting lug 44 shown in top plan
35 view in Figs. 2, 3 and 4, in which is mounted a
striker screw 45 that lies in the same horizontal
plane with the valve stem 42.

The spring 38 of the auxiliary valve 30 is of
sufficient strength to overcome the inertia of the
40 arm 19 and its head 20.

Briefly describing the function and operation
of the auxiliary valve 30, when the operative is
ready to squeeze the flask, with his left hand he
grasps a handle 46 on the free end of the arm 19
45 and swings the latter from the off position shown
in Fig. 2 to the working position shown in Fig. 4.
During the latter part of this swing, the screw 45
strikes the projecting end of the valve stem 42
and forces the latter inwardly, unseating the valve
50 and admitting fluid pressure to the portion of the
line 22 beyond the valve. He then with his
right hand depresses the main valve handle 25
and holds the latter depressed until the squeezing
operation is completed. During this squeezing
55 operation it is necessary for him to hold the
head 20 in its working position (Fig. 4) since, if
he lets go, the valve spring 38 acting through
the stem 42 will push the head 20 to the in-
operative position shown in Fig. 3. Thus, at
60 the inception of and during the flask squeezing
operation both hands of the operative are occu-
pied in safe positions where neither hand can
become accidentally injured.

In the line 23 that serves the flask jolting
65 motor I also preferably interpose an auxiliary
valve designated as an entirety by 30'. As seen by
a comparison of Figs. 5 and 6, the valves 30 and
30' are identical except that the spring 38' of the
valve 30' is weaker than the spring 38 of the
70 valve 30 and, in fact, is of insufficient strength
to overcome the inertia of the head 20 and its
arm 19. On the arm 19 is a lug 47 that extends
into the horizontal plane of the valve stem 42'
of the valve 30'. The valve 30' is normally held
75 closed by both its spring 38' and the differential

air pressure behind it, so that if the operative
loads the flask on the platform 16 while the head
20 is at or between the positions shown in Fig. 3,
and accidentally strikes the main valve handle 27
with his knee, he cannot be injured during the
jolting operation, since the motive fluid cannot
reach the jolt motor until the head 20 has been
swung entirely clear of the vertical path of travel
of the platform and flask, as shown in Fig. 2,
which opens and holds open the auxiliary valve 10
30'. Even if the head be swung to the position
shown in Fig. 3, its arm does not open the aux-
iliary valve 30', so that with the head 20 in or
anywhere between the positions shown in Fig. 3,
the machine is inoperative either for jolting or 15
squeezing the flask. When squeezing, the hands
of the operative cannot be injured because they
are both in safe positions. When jolting, they
cannot be injured by accidental opening of the
main jolt valve because the arm and head are 20
wholly to one side of the path of travel of the
platform and flask.

Manifestly, either of the safety features re-
presented by the auxiliary valves 30 and 30' may
be employed without the other; but the maximum 25
safety of the machine is obtained by the use of
both.

The structural details of the auxiliary safety
valves and their operating devices may, of course,
be varied from those shown and described with-
out departing from the principle of the invention
or sacrificing any of its advantages. Hence, I
reserve all such variations and modifications as
fall within the spirit and purview of the claims.

I claim:

1. The combination with a molding machine
of the squeeze type having a flask supporting plat-
form, a fluid pressure motor for raising said
platform, a platen head movable between posi-
tions above and to one side of said platform, a 40
motive fluid supply line for said motor, and a
manually operable valve in said line, of a self-
closing auxiliary valve in said line, and means
whereby said auxiliary valve is opened when said
head is moved to and held in working position 45
above said platform.

2. The combination with a molding machine
of the squeeze type having a flask supporting
platform, a fluid pressure motor for raising said
platform, a platen head movable between posi-
tions above and to one side of said platform, a 50
motive fluid supply line for said motor, and a
manually operable valve in said line, of a normally
closed auxiliary valve in said line, means
whereby said auxiliary valve is opened when said
head is moved to and held in working position
above said platform, and means automatically
moving said head out of working position and
permitting said auxiliary valve to close if and
when said head is not held in working position. 60

3. The combination with a molding machine of
the squeeze type having a flask supporting plat-
form, a fluid pressure motor for raising said plat-
form, a platen head movable between positions
above and to one side of said platform, a motive
fluid supply line for said motor, and a manually
operable valve in said line, of a normally closed
auxiliary valve in said line, said valve having a
stem projecting exteriorly of said line, means
whereby said auxiliary valve is opened through
contact with said stem when said head is moved
to and held in working position above said plat-
form, and a spring closing said auxiliary valve and
through said stem shifting said head out of 70

working position if and when said head is not held in working position.

4. The combination with a molding machine of the squeeze type having a flask supporting platform, a fluid pressure motor for raising said platform, an arm pivoted to swing laterally above said platform, a platen head on the free end of said arm, a motive fluid supply line for said motor, and a manually operable valve in said line, of a normally closed auxiliary valve in said line, said valve having a stem projecting exteriorly of said line, and a valve closing spring projecting said stem into the path of swing of said arm whereby the latter opens said valve when said head is moved into working position, said spring being strong enough to overcome the inertia of said arm and head thereby requiring the latter to be held in working position to maintain said auxiliary valve open during the squeezing operation.

20 5. The combination with a molding machine of the squeeze type having a flask supporting platform, a fluid pressure motor for jolting said platform, a platen head movable between positions above and wholly to one side of said platform, a motive fluid supply line for said motor, and a knee-operable valve in said line, of a self-closing auxiliary valve in said line, and means whereby said auxiliary valve is opened and held opened when said head is shifted to a position wholly to 30 one side, and out of the path of travel, of said platform and flask.

6. The combination with a molding machine of the squeeze type having a flask supporting platform, a fluid pressure motor for jolting said platform, an arm pivoted to swing laterally above said platform, a platen head on the free end of said arm, a motive fluid supply line for said motor, and a knee-operable valve in said line, of a normally closed auxiliary valve in said line, said valve having a stem projecting exteriorly of said line, and a valve closing spring projecting said stem into the path of swing of said arm whereby the latter opens said valve when said head is swung entirely to one side of said platform, said spring being of insufficient strength to overcome the inertia of said arm and head, whereby said valve remains open so long as its stem is contacted by said arm.

7. The combination with a molding machine of the squeeze type having a flask supporting platform, a fluid pressure motor for raising said plat-

form, a second fluid pressure motor for jolting said platform, a platen head movable between positions above and to one side of said platform, motive fluid supply lines for both of said motors, a manually operable valve in the line serving said first-named motor, and a knee-operable valve in the line serving said second motor, of self-closing auxiliary valves in the respective lines, and means whereby the auxiliary valve in the line serving said first-named motor is opened 10 when said head is moved to and held in working position above said platform, and whereby the auxiliary valve in the line serving said second motor is opened and held open when said head is shifted to a position wholly to one side, and out 15 of the path of travel of, said platform and flask.

8. The combination with a molding machine of the squeeze type having a flask supporting platform, a fluid pressure motor for raising said platform, a second fluid pressure motor for jolting said platform, an arm pivoted to swing laterally above said platform, a platen head on the free end of said arm, motive fluid supply lines for both of said motors, a manually operable valve in the line serving said first-named motor, and a knee- 20 operable valve in the line serving said second motor, of a normally closed auxiliary valve in the line serving said first-named motor, said valve having a stem projecting exteriorly of said line, a valve closing spring projecting said stem 25 into the path of swing of said arm whereby the latter opens said valve when said head is moved into working position, said spring being strong enough to overcome the inertia of said arm and head thereby requiring the latter to be held in 30 working position to maintain said auxiliary valve open during the squeezing operation, and a normally closed auxiliary valve in the line serving said second motor, said last-named valve having a stem projecting exteriorly of said last-named 35 line, and a valve closing spring projecting said last-named stem into the path of swing of said arm whereby the latter opens said last-named valve when said head is swung entirely to one side of said platform, said last-named spring being of insufficient strength to overcome the inertia of said arm and head, whereby said last-named valve remains open so long as its stem is contacted by said arm.

HENRY O. MAGNUSON.
